(57) **CLAIM**

The ornamental design for a motorcycle, as shown and
described.

DESCRIPTION

FIG. 1 is a frontal perspective view of a motorcycle showing
our new design;

FIG. 2 is a rear perspective view thereof;

FIG. 3 is a side elevational view of one side thereof;

FIG. 4 is a side elevational view of the other side thereof;

FIG. 5 is a front elevational view thereof;

FIG. 6 is a rear elevational view thereof; and,

FIG. 7 is a top plan view thereof.

The broken line showing of the wheels, tires and brake
rotors is for illustrative purposes only and forms no part of
the claimed design. The unillustrated bottom view forms no
part of the claimed design.
